DESIGN.

B. F. CORNELL.
ARM FOR DISPLAY STANDS.

No. 28,364

Patented Mar. 8, 1898

UNITED STATES PATENT OFFICE.

BENJAMIN F. CORNELL, OF CHICAGO, ILLINOIS.

DESIGN FOR AN ARM FOR DISPLAY-STANDS.

SPECIFICATION forming part of Design No. 28,364, dated March 8, 1898.

Application filed January 20, 1898. Serial No. 667,350. Term of patent 7 years.

To all whom it may concern:

Be it known that I, BENJAMIN F. CORNELL, a citizen of the United States, residing at Chicago, in the county of Cook and State of Illinois, have invented and produced a new and original Design or Useful Shape for a Display or Show Stand Arm, of which the following, in connection with the accompanying drawings, is a full, clear, and exact specification.

In the said drawings, Figure 1 is an inner face view of a display or show stand arm embodying my design. Fig. 2 is an edge view thereof; and Fig. 3 is a transverse section taken on the line 3 3, Fig. 2.

The leading features of my design consist of a display or show stand arm having the rosette-like formations A B at or near each end thereof.

As shown in the drawings, one of the rosette-like portions A B is arranged at each end of the arm C, and between these two rosette-like portions A B is also located a third rosette-like portion D, which occupies a substantially central or mid-length position with reference to the other two.

The arm proper, C, is substantially straight, with parallel sides between the rosettes A B D, and is formed with longitudinal flutes or ribs c, which appear on both sides thereof, as indicated in Fig. 3, and its entire width is slightly less than the diameters of the rosettes A B D.

Each of the rosette-like portions is provided with a central countersink a, surrounded by a plurality of radiating countersinks a', and the center of the countersink a is apertured or perforated, as shown at a'', the countersinks a' having beveled edges, as clearly shown in the drawings.

Having thus described my invention, what I claim as new therein, and desire to secure by Letters Patent, is—

The new and original design or useful shape for an arm for display or show stands, substantially as herein shown and described.

BENJAMIN F. CORNELL.
